UNITED STATES PATENT OFFICE

2,508,553

DISPLAY SIGN

Erwin Wagner, Chicago, Ill., assignor to Wagner Sign Service, Incorporated, Chicago, Ill., a corporation of Illinois

Application June 6, 1945, Serial No. 597,899

5 Claims. (Cl. 40—130)

1

This invention relates to display signs of the general type disclosed, for example, in my Patents Nos. 2,048,040 and 2,158,343.

Display signs of this type are usually provided with a translucent panel, e. g., a glass panel, mounted in a suitable box-like structure at one side thereof and with members forming in front of the panel vertically superposed horizontally extending parallel bars for removably supporting so-called silhouette letters, characters, figures or other symbols assembled on the bars to form a desired message. The panel may be illuminated from the back and the characters or symbols forming such message appear in bold silhouette outline against the illuminated background. Signs of this type are well known and widely used, for example, as marquee signs in front of motion picture theaters.

The present invention is particularly concerned with improvements relating to the arrangement and mounting of the glass panels which form the translucent background for the silhouette letters or characters of such signs.

Single glass panels may be used and are used only in relatively small sign structures. In large signs, which may measure from 5 to 10 feet and more in height and in excess of 20 feet in length, a single panel would be impractical, and prior structures therefore provide a plurality of panels mounted in sections arranged side by side to form the translucent background. Each panel section may again be of considerable size, depending on the over-all size of the sign, and such subdivision is therefore insufficient to overcome certain drawbacks attending the mounting of the panels. Each panel may cover a relatively large area, and may prevent ready access to interior structures. Maintenance, repair and replacement of parts are adversely affected. Accidental breakage of such a large panel section introduces numerous risks, dangers and may occasion considerable expenses.

The shortcomings and drawbacks of prior structures are eliminated by the present invention which contemplates, among others, the objects and features briefly outlined below:

One of the objects of the invention is concerned with the provision of a plurality of vertically extending frames which may be easily mounted in the sign side by side, forming a framework for receiving a plurality of translucent panels adapted to form the background for the silhouette letters or characters. The frames may be mounted in the sign without the translucent panels, and the panels may be subsequently inserted therein and

2

may be individually removed therefrom. Mounting and dismounting of the glass panels is thus facilitated and rendered safe.

Another object relates to the provision of means in each frame for receiving a plurality of panels or panel sub-sections, one superimposed vertically upon the other in overlapping relationship. Each panel sub-section within each frame may be introduced into its place or may be removed therefrom without disturbing the remaining panel sub-sections.

The background for the silhouette letters or characters of the new sign is thus horizontally subdivided into a plurality of frames forming horizontally extending fields, each field comprising a plurality of vertical superimposed panels or panel sub-sections extending in a generally common frontal plane. Each panel sub-section within each frame permits ready access to the interior of the sign within and adjacent the area covered thereby. The arrangement thus facilitates maintenance, repair or replacement of parts.

Details of the invention will appear from the following description which is rendered with reference to the accompanying drawings. In these drawings,

Fig. 1 illustrates an embodiment of the new sign in elevation as seen from the front thereof;

Fig. 2 shows, on an enlarged scale, a front view of one complete frame with its vertically superimposed overlapping panel sub-sections, and parts of adjacent frames holding similar panel sub-sections;

Fig. 3 is a diagrammatic section through the sign along lines 3—3 of Figs. 1 and 2;

Fig. 4 represents an enlarged section through the sign along lines 4—4 in Figs. 2, 3 and 5;

Fig. 5 shows a front view of part of the frame and panel sub-section structure illustrated in Fig. 2 with some parts broken away and in section taken approximately along lines 5—5 in Fig. 4; and

Figs. 6 and 7 illustrate one of the panel sub-sections in front and in end view, respectively.

The drawings are not to scale. Parts in some of the views are distorted at the expense of the other parts so as to bring out details with greater clarity than would be otherwise possible. Like parts are indicated by like reference numerals throughout the drawings.

Referring now to the drawings, the sign comprises a box-like structure having a back wall 11, a top wall 12 and a bottom wall 13, as is particularly apparent from Fig. 3. At the front of the sign is a display opening 14 defined by the

marginal border 15. Angular members 17-18 are disposed within the box structure of the sign, as shown in Fig. 3, forming with the marginal borders 15 the recesses or channels 19 and 20 for receiving the various frames which are generally indicated in Fig. 1 by No. 1 to No. 5, inclusive. Five frames are assumed to be provided in the embodiment Fig. 1, but it is understood, of course, that more or less frames may be used according to needs.

Each frame is constructed similarly, and therefore the description of one will suffice for all. Frame No. 3 may be described more in detail with reference to Figs. 2-5, inclusive. The frame comprises two cross-sectionally L-shaped members 25-26 connected by eight bars numbered 27-34, inclusive. Each bar is provided with legs, as indicated in connection with bar 27 at 35-36 and bar 34 at 37-38, these legs being suitably fastened, e. g., welded to the bars and also to the corresponding upright frame members 25-26, respectively.

The general structure of the frame is thus reminiscent of a ladder, with the bars forming the rungs thereof. The bars are provided for the purpose of receiving and supporting the silhouette letters, characters or symbols as described in my previously mentioned patents. Eight such bars are shown in Figs. 1 and 2 in connection with the frame No. 3. It is understood, of course, that this is done for the sake of convenience and is not intended to indicate any limitation. More or less bars may be provided as required in accordance with the size and purpose of the sign.

Each of the remaining frames, Nos. 1-2 and 4-5, respectively, is constructed similarly. Each frame is put in place by lifting it, with the upper ends of the uprights 25 and 26 inserted into the recess or channel 19 (Fig. 3), until the lower ends of the uprights 25-26 clear the edge of the opening 14 defined by the bottom margin 15, whereupon the uprights are dropped into the lower channel 20.

Suitable adjustable tie rods, indicated in Fig. 3 at 40, may be provided for securing the rearwardly extending portions 41-42 of the frame uprights 25-26, respectively, to the rear wall 11 of the sign box. The tie rods constitute a support for the frames and therewith for the glass panels provided in each frame. They prevent rattling and counteract the effect of wind pressure.

The various frames may be laterally tied together after insertion into the sign by means of suitable spring clips (not shown) clamped over the uprights of adjacent frames. Any other suitable and approved means for tying the frames laterally together may, of course, be used.

The crossbars such as 27-34 of the various frames are in horizontal alignment, forming parallel horizontally extending continuous supports for the silhouette letters or characters which are to be assembled thereon. The alignment of the crossbars of the sign is apparent from Figs. 1, 2 and 4. It will be seen, for example, that the crossbar 27 of frame 3 is in horizontal alignment with the crossbar 45 of frame 2 and also with the crossbar 46 of frame 4. The same is true of the lowermost crossbar 34 of frame 3 which is in horizontal alignment with crossbar 47 of frame 2 and also with crossbar 48 of frame 4. All the remaining crossbars 28-33 of frame 3 are in similar horizontal alignment with the corresponding crossbars of adjacent frames Nos. 2 and 4 and the crossbars in the latter frames are simi-

larly aligned with the crossbars in frames 1 and 5, respectively.

The means for mounting in each frame the translucent panel sub-sections, which form the background for the message assembled on the crossbars, comprises U-shaped channel members suitably attached, for example, by welding, to the inside of the rearwardly projecting extensions 41 and 42, respectively of the uprights 25 and 26 of each frame. For example, the rearwardly projecting extension 41 of the upright 25 carries four U-shaped channels marked in Fig. 3 from bottom to top by numerals 50-51-52-53. These channels are arranged at an angle to the frontal plane of the sign and in overlapping relationship; i. e., the top of each channel is disposed in back of the bottom of the vertically successive channel. Putting it in other words, the bottoms of the channels are disposed in a common plane, but each channel slants backwardly so that its top clears the bottom of the next channel. The channels face laterally inwardly from the sides of the frame, and each channel is provided at its bottom with a leg for supporting the panel inserted therein. For example, the channel 53, Figs. 3 and 5, which is attached to the rearwardly projecting extension 41 of the upright member 25, is provided with the bottom leg 54. Similarly, the channel 55, attached to the rearwardly projecting extension 42 of the upright frame member 26, is provided with the bottom leg 57. These two laterally inwardly facing channels hold the panel sub-section 60 which is inserted therein from the top, as indicated in Fig. 3. Each channel member on the rearwardly projecting extension 41 of the upright frame member 25 has a similar companion channel member carried by the rearwardly projecting extension 42 of the upright 26. The companion U-shaped channel for the channel 52 on the upright extension 41 is attached to the extension 42 of upright 26 and is indicated in Fig. 5 by numeral 56. The channels 52 and 56 support the panel sub-section 61 disposed below the panel section 60. The mounting of the panel sub-section 62 disposed below panel sub-section 61 and of the bottom panel sub-section 63 is similar.

These panel sub-sections 60-63 are thus each provided on an incline, slanting back from the frontal plane of the sign, with the top edge of panel sub-sections 61 in back of the bottom edge of panel sub-section 60; the top edge of panel sub-section 62 in back of the bottom edge of panel sub-section 61; and the top of panel sub-section 63 in back of the bottom of panel sub-section 62.

The incline of these panel sub-sections, as shown in Fig. 3, is very much exaggerated due to the distorted scale on which the different parts are illustrated within the available drawing space. It should be considered in connection with this arrangement that each of these panel sub-sections may be, for example, 2 feet high and $\frac{1}{4}$ inch thick. The channel members 53-55, 52-56, etc., which hold the different panel sub-sections, are made of material e. g., $\frac{1}{8}$ inch thick or even less. The angular distortion which results in a practical embodiment is, therefore, negligible. In other words, the panel sections are disposed at an angular incline, e. g., approximately $\frac{1}{4}$ inch to every 2 feet of height. For all intents and purposes the panel sub-sections may be considered to be in vertical alignment and actually create the frontal impression of being of an integral structure; that is to say, when looking

at the sign from the front there is no break visible in the background, the joining edges, that is, the lower edges of the panel sub-sections, being concealed behind corresponding crossbars, as indicated in Fig. 2, and the impression is that the sign is provided with a single, uninterrupted background panel.

The topmost panel sub-section 65, in each frame, is also mounted in U-shaped channel members, but in this case there is on each side of the panel sub-section a pair of channel members at the bottom and one pair of channel members near its top. The bottom channels for the panel sub-section 65 are indicated in Figs. 3, 4 and 5 by numerals 66-67. Each is provided with a supporting leg indicated at 68-69, respectively. The companion U-shaped channels on the top are marked by numerals 70-71.

Proper placing of the top panel sub-section 65 is accomplished by inserting the panel sub-section edgewise between the crossbars, for example, between the crossbars 27 and 28 into the interior of the sign box, tilting the panel sub-section, and slipping it into the uppermost channels 70-71 until the lower edge clears the channels 66 and 67, whereupon the panel sub-section 65 is moved forward, slipped into the channels 66-67 and dropped into supporting engagement with the legs 68 and 69. Each of the remaining inclined panel sub-sections 60-63 is inserted similarly by slipping each sub-section into the structure edgewise through and between correspondingly placed crossbars, raising and tilting it within the sign box, and slipping it into the corresponding companion channels, whereupon the panel sub-section is dropped within its mounting channels until it rests with its opposite bottom edges on the legs extending from the associated channels. In fully inserted positions, the panel sub-section 65 rests on the legs 68-69 of channels 66-67; panel sub-section 60 rests on the legs 54, 57 of channels 53, 55; and each of the panel sub-sections 61, 62, 63 rests similarly on legs projecting inwardly from its mounting channels such as 52, 51 and 50, respectively.

Within the sign box, mounted on shelves provided on the rear wall thereof, are provided suitable incandescent lamps or other illuminating means which furnish the illumination for the panel sub-sections forming the background panel for the silhouette letters or characters assembled on the crossbars in front thereof.

Each panel sub-section within each frame is thus vertically movable and permits access to the interior of the structure to the extent of the area which it covers and including the interior which surrounds such area. Maintenance, repair and replacement of parts is facilitated because the new structure enables the maintenance man to gain access to any portion and section of the sign that may need attention, without disturbing the remaining structure.

For example, as indicated in Fig. 3, it is possible to gain access to the lamps in back of the panel sub-section 60 simply by raising this sub-section and temporarily supporting it on an S-shaped member 75, one end of which is hooked over the crossbar 27 and the other end of which supports the raised panel sub-section 60 by engagement with its lower edge. The maintenance man can then do the necessary interior repair, replacement or adjustment work in back of the panel sub-section 60 without disturbing any other panel sub-section and without any trouble whatsoever. The same holds true of every other por-

tion of the sign covered by any other panel sub-section in any of the remaining frames.

Attention is directed to the fact that the showing of the hook-like supporting member 75 (Fig. 3) in its relation to the crossbars and to the panel sub-section 60 is distorted because of distortions in the dimensions and consequently in the placement of parts necessitated for illustrating and for describing the invention. The hook 75 would in reality hang downwardly, and the panel sub-section 60 would be in a substantially vertical position. The panel sub-sections 61, 62 and 63 would also be substantially vertical, in a practical embodiment, as will be understood from previous explanations.

Each panel sub-section may be provided at its bottom edge with a protective strip 80, as indicated in Figs. 6 and 7 in connection with the panel sub-section 60. This protective strip may be a thin, film-like strip of metal, preferably a resilient metal such as copper, or may be a plastic material, rubber and the like, or a suitable tape. It may be attached to the edge of the panel section as required, e. g., by cementing it thereon, or in the case of a plastic composition or rubber, by spraying or by painting it thereon. This protective strip is provided for the purpose of resiliently supporting each panel sub-section on its corresponding legs such as 54-57 for panel sub-section 60, or 68-69 for sub-section 65, respectively, and for the purpose of minimizing damage in case of accidental breakage. Laminated glass may be used for making these panel sub-sections if desired.

The invention has been described in connection with a specific form of silhouette letters, symbols or characters made in accordance with the previously mentioned patents and requiring suitably formed crossbars as shown in the drawings. It is clear, of course, that the form of silhouette letters or characters is immaterial and does not form a part of this invention. Different type letters and symbols and differently constructed crossbars may be used in connection with the structure and arrangement of the sign described herein. It is also understood that the panel sub-sections need not be made of translucent glass, but may be made of any desired and suitable material. Metal sheets, for example, glazed sheets, may be used in place of the glass panel sub-sections shown in the drawings, in a sign, for example, which does not depend for its display effect on the translucence of the background. The corresponding panel sub-sections will then permit easy and safe mounting and will give the accessibility for repair and maintenance of the sign in the same manner as described in connection with the translucent panel sub-sections of the sign shown in the drawings.

Changes may be made within the scope and spirit of the appended claims which define what is believed to be new and desired to have protected by Letters Patent of the United States.

I claim:

1. In a changeable sign having a boxlike housing forming a rectangular frontal opening at one side thereof and having a plurality of vertically successive panels which extend across said opening to form a background for articles assembled for display in front thereof, a device for individually mounting said panels to furnish the appearance of a single substantially uninterrupted vertically extending display background surface and to permit raising of each panel individually to gain access to the interior of said sign along

an area covered by such panel without disturbing any other panel, said device comprising a pair of horizontally spaced uprights, the opposite free ends of said uprights being removably disposed in recesses formed in the frontal part of said housing which defines said opening at the top and bottom thereof, respectively, a plurality of vertically successive vertically spaced crossbars extending horizontally between said uprights and endwise connected therewith, an extension projecting rearwardly from each upright intermediate its free ends, and a plurality of cross-sectionally U-shaped channel members carried by each extension and laterally inwardly projecting therefrom to form a plurality of vertically successive pairs of generally vertically extending horizontally spaced and laterally inwardly facing cooperating channels, each pair of cooperating channels for removably receiving one of said panels in sliding engagement with opposite lateral edges thereof, each cooperating pair of channels being disposed at a rearwardly slanting angle in upwardly, rearwardly, overlapping relationship with the vertically next successive cooperating pair of channels, whereby each panel may be individually raised in edgewise sliding engagement with its cooperating pair of channels by applying a lifting force to its frontally accessible bottom edge which extends horizontally between said uprights to form an opening in said background surface which exposes the interior of said sign substantially for the area covered by such panel.

2. In a changeable sign having a boxlike housing forming a rectangular frontal opening at one side thereof and having a plurality of vertically successive panels which extend across said opening to form a background for articles assembled for display in front thereof, a device for individually mounting said panels to furnish the appearance of a single substantially uninterrupted vertically extending display background surface and to permit raising of each panel individually to gain access to the interior of said sign along an area covered by such panel without disturbing any other panel, said device comprising a pair of horizontally spaced uprights, the opposite free ends of said uprights being removably disposed in recesses formed in the frontal part of said housing which defines said opening at the top and bottom thereof, respectively, a plurality of vertically successive vertically spaced crossbars extending horizontally between said uprights and endwise connected therewith, an extension projecting rearwardly from each upright intermediate its free ends, a plurality of cross-sectionally U-shaped channel members carried by each extension and laterally inwardly projecting therefrom to form a plurality of vertically successive pairs of generally vertically extending horizontally spaced and laterally inwardly facing cooperating channels, each pair of cooperating channels for removably receiving one of said panels in sliding engagement with opposite lateral edges thereof, each cooperating pair of channels being disposed at a rearwardly slanting angle in upwardly, rearwardly, overlapping relationship with the vertically next successive cooperating pair of channels, whereby each panel may be individually raised in edgewise sliding engagement with its cooperating pair of channels by applying a lifting force to its frontally accessible bottom edge which extends horizontally between said uprights to form an opening in said background surface which exposes the interior of said sign substantially for the area covered by such panel.

8
tially for the area covered by such panel, and means for attachment to one of said crossbars and to the lower edge of a raised panel, respectively, for holding such panel in elevated position to permit secure and unimpeded access to the corresponding interior area of said sign.

3. In a changeable sign having a boxlike housing forming a rectangular frontal opening at one side thereof and having a plurality of vertically successive panels which extend across said opening to form a background for articles assembled for display in front thereof, a device for individually mounting said panels to furnish the appearance of a single substantially uninterrupted vertically extending display background surface and to permit raising of each panel individually to gain access to the interior of said sign along an area covered by such panel without disturbing any other panel, said device comprising a pair of horizontally spaced uprights, the opposite free ends of said uprights being removably disposed in recesses formed in the frontal part of said housing which defines said opening at the top and bottom thereof, respectively, a plurality of vertically successive vertically spaced crossbars extending horizontally between said uprights and endwise connected therewith, an extension projecting rearwardly from each upright intermediate its free ends, a plurality of cross-sectionally U-shaped channel members carried by each extension and laterally inwardly projecting therefrom to form a plurality of vertically successive pairs of generally vertically extending horizontally spaced and laterally inwardly facing cooperating channels, each pair of cooperating channels for removably receiving one of said panels in sliding engagement with opposite lateral edges thereof, each cooperating pair of channels being disposed at a rearwardly slanting angle in upwardly, rearwardly, overlapping relationship with the vertically next successive cooperating pair of channels, whereby each panel may be individually raised in edgewise sliding engagement with its cooperating pair of channels by applying a lifting force to its frontally accessible bottom edge which extends horizontally between said uprights to form an opening in said background surface which exposes the interior of said sign substantially for the area covered by such panel, and a generally S-shaped hanger for attachment at one end to one of said cross-bars and at the other end to the lower edge of a raised panel, respectively, for holding such panel in elevated position to permit secure and unimpeded access to the corresponding interior area of said sign.

4. In a changeable sign having a boxlike housing forming a rectangular frontal opening at one side thereof and having a plurality of vertically successive panels which extend across said opening to form a background for articles assembled for display in front thereof, a device for individually mounting said panels to furnish the appearance of a single substantially uninterrupted vertically extending display background surface and to permit raising of each panel individually to gain access to the interior of said sign along an area covered by such panel without disturbing any other panel, said device comprising a pair of horizontally spaced uprights, the opposite free ends of said uprights being removably disposed in recesses formed in the frontal part of said housing which defines said opening at the top and bottom thereof, respectively, a plurality of vertically successive vertically spaced crossbars

extending horizontally between said uprights and endwise connected therewith, an extension projecting rearwardly from each upright intermediate its free ends, and a plurality of cross-sectionally U-shaped channel members carried by each extension and laterally inwardly projecting therefrom to form a plurality of vertically successive pairs of generally vertically extending horizontally spaced and laterally inwardly facing cooperating channels, each pair of cooperating channels for removably receiving one of said panels in sliding engagement with opposite lateral edges thereof, each cooperating pair of channels being disposed at a rearwardly slanting angle in upwardly, rearwardly overlapping relationship with the vertically next successive pair of channels with the upper ends of the channels in back of and adjacent to the lower ends of the corresponding vertically successive channels, whereby each panel is disposed in a plane slightly rearwardly tilting with respect to the bottom plane of the vertically next successive panel by an amount which corresponds substantially to the thickness thereof and whereby each panel may be individually raised in edgewise sliding engagement with its cooperating pair of channels by applying a lifting force to its frontally accessible bottom edge which extends horizontally between said uprights to form an opening in said background surface which exposes the interior of said sign substantially for the area covered by such panel.

5. In a changeable sign of the class described having a boxlike housing forming a rectangular frontal opening at one side thereof, a pair of horizontally spaced uprights, the opposite free ends of said uprights being removably disposed in top and bottom recesses, respectively, formed in the side of said housing which defines said frontal opening, an extension projecting rearwardly from each upright intermediate its free ends, a plurality of vertically spaced vertically disposed channel members carried by each extension near the top thereof and laterally inwardly projecting therefrom to form vertically successive pairs of laterally inwardly facing top retainer means for removably holding a top dis-

play panel sub-section in vertical position to cover an area of said frontal opening immediately below the top edge thereof, and a plurality of cross-sectionally U-shaped vertically downwardly successively disposed channel members carried by each extension below said top retainer means and laterally inwardly projecting therefrom to form pairs of laterally inwardly facing cooperating channels, each pair of cooperating channels for removably receiving a display panel sub-section to cover a corresponding area of said frontal opening below said top display panel sub-section, each cooperating pair of channels being disposed at an angle with the upper ends of the channels in back of and adjacent to the lower ends of the channels of the vertically next successive pair, whereby each of the display panel sub-sections below said top display panel sub-section is disposed in a plane slightly rearwardly tilting by an amount which corresponds substantially to the thickness thereof and whereby each display panel sub-section may be individually raised by applying a lifting force to its bottom edge to expose the interior of said sign substantially for the area covered by said display panel sub-section.
